YIELDING TORQUE INDICATING TOOL

Allen J. Mellert, Cleveland, Ohio, assignor, by
mesne assignments, to Diversified Designing &
Machine Products Corporation, Cleveland,
Ohio, a corporation of Ohio

Application November 30, 1945, Serial No. 631,972

8 Claims. (Cl. 81—52.5)

1

This invention relates to tools and particularly to those having a work-engaging head and a handle by means of which force or torque is applied to the work. Among the tools to which the invention is applicable may be mentioned wrenches, screw drivers, and various forms of tamping or punching devices.

In hand tools of these types it has been found desirable to indicate in some way to the operator when a predetermined amount of torque or force has been applied to the work. Such an indication is necessary where an excessive amount of tightening of a fastening means would injure either the article being fastened or the fastening means itself, and in other cases is desirable in saving a needless amount of work exceeding that of the predetermined amount found to be sufficient for a particular application.

In devices of this type, some form of resilient means, usually in the form of a coil spring, is used to drive the work-engaging member, and it is usually necessary to multiply the force exerted by the spring so that the spring itself need not be excessively stiff and difficult to control. In the past various forms of mechanical linkages have been devised to accomplish this multiplication of the force. Friction between the moving parts, however, has been a constant source of annoyance in viating the results, as any change in the ease with which the parts articulate is reflected in the amount of torque or force applied to the work member.

An object of the present invention is to provide a device which will accomplish the multiplication of force between the resilient driving means and the work-engaging member in a tool and which will not be subject to the above objections.

Another object is to provide an adjustment for the force applying means whereby to predetermine the force or torque at which the tool operates.

Another object is to provide a visual indicating means to apprise the operator that the predetermined effect has been accomplished.

A further object is to provide means whereby the resistance offered by the handle to the efforts of the operator is suddenly relaxed when the predetermined effect has been produced, thus furnishing him an indication in addition to the visual one.

These objects I accomplish in a simple and effective manner by providing a work-engaging member which moves relative to the handle when, while the member is stopped by the re-

2

sistance of the work, the handle continues on, and by providing a differential cylinder wherein the unit pressure produced by a small piston, under action of a main spring, is multiplied over the area of a large piston to provide a large force for application to the work-engaging member and wherein the working fluid, such as oil, maintains the pistons in lubricated condition. The operator is advised when the predetermined effect has been produced by the sudden relaxation of the drive furnished by the above means, and in addition an electric light is provided which cooperates with the other parts to give him the same information.

Referring now to the drawings, Fig. 1 is an axial section through a wrench embodying my invention; Fig. 2 is an elevational view thereof; Fig. 3 is a view similar to Fig. 1 but showing the parts in different relative positions; and Fig. 4 is a transverse section taken on the line 4—4 of Fig. 3.

In the drawings I have illustrated a preferred embodiment of my invention in which a handle 10 is provided with a jaw 11 pivoted at 12 to extensions or ears 13 on the handle. The jaw itself may be separable from a pivoted block 14 so as to be interchangeable with jaws of other sizes or with other types of work-engaging heads. Normally, the jaw or head is forcibly held in alignment with the handle in the position illustrated in Fig. 3. In operation, however, when a workpiece, such as the nut N, has been tightened to such a degree that a torque above a predetermined amount must be applied to turn it further, the alignment maintaining force is overcome. Since the rotation of the head is then retarded, continued movement of the handle by the operator causes the tool to break at the pivot 12. The sudden relaxation indicates to the operator that the desired torque has been applied. Additional indication is furnished by a visual signal in the form of an electric light, the circuit of which is closed upon a predetermined amount of relative turning of the handle and jaw.

The alignment maintaining force mentioned is preferably produced by means of a compression spring 15 bearing at one end against a reaction member 16 and at the other end against a spring seat 17 on an elongated piston or ram 18. The ram 18 is slidable in a differential hydraulic cylinder 19 which is provided with an appropriate packing or seal at 20. The cylinder is enlarged at 21 to accommodate a piston 22 of an area many times that of a piston 18. The piston 22 is provided with a cup-shaped washer

23 of leather or other suitable material and a light spring 24 is interposed between the washer and the end of the large cylinder to maintain the parts in proper position. The piston 22 is also provided with a hardened renewable wearing surface at 25 which is adapted to bear against the pivoted block 14. A flat 26 is formed on the block, for engagement with the piston, and terminates in slightly rounded corners 27. Normally, the piston 22 bears against the flat to hold the block and jaw in alignment with the handle. Upon relative turning of the block, however, a corner 27 operates as a high point, or portion of increased radius, on a cam and cams the piston inwardly. Abutments may be provided at 44 to prevent inadvertent ejection of the piston before the block 14 is secured in place.

It will be understood that the cylinder 21 is filled with oil or other suitable fluid and that the force exerted by the spring 15 through the ram 18 is multiplied, by the ratio of the squares of the diameters of the two pistons, to provide a greatly increased force against the block. Conversely, a small movement imparted to the piston 22 by means of the pivoting block produces a correspondingly greater movement of the piston 18, and hence a longer spring can be utilized at 15, the advantage of which will be later pointed out.

To accommodate the electric light bulb and its battery, a housing 30 is provided, which housing forms an extension of the handle. A socket 31 for the bulb 32 is clamped against the end of the housing by means of a threaded, transparent cover 33. The battery 34 is pressed into contact with the bulb by a spring 35 which, in turn, makes contact with the end of the battery and with an insulated, elongated contact 36 carried in an inwardly extending sleeve 37 on the housing. The housing is rotatably adjustable with respect to the handle 10 and may be clamped in adjusted position, through the intermediacy of a clamping nut 38 which engages a rib 39 on the housing and is threaded on the handle.

A circuit for the light is established when the piston 18 has been ejected sufficiently far from the hydraulic cylinder to engage the contact 36. Current may then flow from the battery 34 through the light 32, socket 31, housing 30, sleeve 37, reaction member 16, spring 15, spring seat 17, piston 18, contact 36, and spring 35, and back to the battery. This circuit is normally open at the contact 36, as illustrated in Fig. 3.

The compression spring 15 may be adjustably pre-loaded so as to predetermine the torque at which the tool will operate. To this end the reaction member 16 is provided in the form of a traveling nut, threaded upon the sleeve 37 of the housing 30. Lugs 40 are integrally formed on the member and are slidable in slots 41 in the handle 10, to prevent rotation of the traveling nut. One or both of the lugs may conveniently serve as an indicator, as shown at 42, for co-operation with suitable indicia on the handle, whereby the tool may be calibrated in inch-ounces, foot-pounds, or other suitable units. The position of the reaction member, and thereby the pre-loading of the spring, may be accomplished by loosening the clamping nut 39 and rotating the housing 30.

The provision of the force multiplying hydraulic feature enables the use of a lighter and longer spring and a number of advantages are gained thereby. One advantage is that the parts need not be as rugged, and therefore as wasteful of material, as would be necessary with a far more

powerful spring. Another advantage is that the increased length of the spring enables an increase in the length of adjustment required to cover the intended range of the tool. This results in a greater spread of the indicia marks with an attendant increase in accuracy of adjustment. An additional advantage derived from the greater length of travel is the increase in accuracy with which the position of the electrical contact for the visual indicator may be controlled.

While I have illustrated the tool as having a pivoted head which is normally maintained in position by the force of the piston against a flat cam formation, the cam being adapted to move the piston when the head swings from normal position, it will be apparent that other arrangements could be used.

Thus while I have illustrated a specific embodiment of my invention, I do not intend to be limited thereby, as the changes and modifications here suggested and others apparent to one skilled in the art may be made within the spirit and scope of my invention.

I claim:

25 1. A tool comprising a hollow handle, a work-engaging head pivotally carried by the handle and normally aligned therewith, a cam drivingly secured to the head, a hydraulic cylinder in the handle, the cylinder having an incompressible fluid therein, two pistons of different areas slideable in the cylinder, the larger piston being operable by the cam, an adjustable reaction member, a compression spring between the smaller piston and the reaction member, a battery, an electric light, a stationary contact, and a circuit in part through the contact and through the smaller piston and completed when, upon sufficient misalignment of the head, the smaller piston is forced a predetermined distance from the cylinder to compress the spring and engage the contact.

2. A yielding torque applying tool comprising a hollow handle, a pair of communicating aligned cylinders within the handle one materially larger than the other, the cylinders having incompressible fluid therein, a work-engaging head pivotally carried by the handle, a piston positioned in each of the cylinders with the larger cylinder receiving a larger piston than the other cylinder, means to slide the larger piston axially into the cylinder upon relative pivoting movement of the head with respect to the handle, a spring resisting the outward movement of the smaller piston from its cylinder, the head being independent of the cylinders and both of the pistons in the work engaging action of the head and not being connected to the cylinders and pistons, and an adjustable spring-acting device within the handle opposing resistance to the outward movement of the smaller piston.

3. In a yielding torque applying tool, the combination of a hollow handle having adjacent one end a comparatively large cylinder and having within the handle back of such large cylinder a smaller cylinder in communication with the large cylinder, the cylinders having an incompressible fluid therein, a piston in the large cylinder, a work-engaging head pivotally carried by the handle and coacting with an abutment member at the outer end of the piston in the large cylinder, a piston rod axially slideable from the opposite end into the small cylinder, a spring seat secured to said piston rod beyond its cylinder, a compression spring within the handle bearing at one end against the spring seat, an adjustable 70 abutment member within the handle against

which the other end of the spring bears and a rotatable device on the handle for variably positioning the abutment member to compress the spring adjustably.

4. A tool of the character described comprising a tubular handle carrying within it adjacent one end a comparatively large cylinder and then a smaller cylinder communicating with the large cylinder, the cylinders having an incompressible fluid therein, a work engaging member pivoted to the handle and having a cam action against a piston in the large cylinder, a piston rod occupying the smaller cylinder and extending in the opposite direction, a spring seat carried by the piston rod, a longitudinally adjustable abutment within the handle having a lug occupying a longitudinal slot in the handle and a helical spring within the handle compressed between said abutment member and spring seat, whereby the amount of compression of the spring may be visibly indicated by graduations on the handle adjacent the slot.

5. A yielding torque applying tool comprising a hollow handle forming a cylinder and carrying adjacent one end a pivotally mounted work-engaging head, a piston slidably mounted in the handle and carrying a removable abutment screw against which the pivoted head may exert a camming action, a smaller cylinder within the handle in communication with the larger cylinder, the cylinders having an incompressible fluid therein, a piston in the smaller cylinder projecting beyond it and carrying a spring seat, a spring-engaging said seat and means for putting said spring under compression.

6. A tool comprising a hollow handle, a work-engaging head pivotally carried by the handle and normally aligned therewith, a cam drivingly secured to the head, a pair of hydraulic cylinders in the handle in open communication with each other, the cylinders having an incompressible fluid therein, two pistons of different areas axially slidable in the respective cylinders, the larger piston being operable by the cam, a reaction member, a compression spring between the smaller piston and the reaction member, a battery, an electric light, a normally open circuit for the light and battery, and means for closing the circuit by the movement of the smaller piston when, upon sufficient misalignment of the head, the smaller piston is forced a predetermined distance out of the cylinder.

7. A yielding torque applying tool comprising a hollow handle, a work engaging head pivotally carried by the handle and normally aligning therewith but adapted to be swung to a position at an angle thereto, axially slidable abutment means within the handle against which said work-engaging head may exert a camming action, said

head and said means being in contact to transmit torque from the handle to the head, a spring setting up a resistance to the movement of said abutment means, a longitudinally movable reaction member engaging said spring, a piston within and movable longitudinally of the handle upon camming movement of said head on the abutment means, a hollow housing rotatably mounted on the handle and having a threaded engagement with said reaction member, a battery in the hollow housing, an electric lamp carried by the housing and in open circuit electric connection with the battery and means within the hollow handle for completing the circuit from the lamp to the battery when torque applied to the handle has swung it to a predetermined angle with the head and has moved said piston longitudinally a predetermined amount.

8. A tool comprising a hollow handle, a pair of aligned communicating hydraulic cylinders within the handle, the cylinders having an incompressible fluid therein, a larger piston and a smaller piston axially slidable in the respective cylinders, a work-engaging head relatively movably carried by the handle and in contact with the larger piston to slide the larger piston into its cylinder upon relative movement of the head and handle, a spring resisting the expulsion of the smaller piston from its cylinder, a spring release member carried by the handle, a battery, an electric light, a normally open circuit for the light and battery, and means carried by the smaller piston for closing the circuit when, upon sufficient misalignment of the head, the smaller piston is forced a predetermined distance out of its cylinder.
